UNITED STATES PATENT OFFICE.

JAMES M. SPANGLER, OF CANTON, OHIO, ASSIGNOR TO THE HOOVER SUCTION SWEEPER COMPANY, OF NEW BERLIN, OHIO, A CORPORATION OF OHIO.

SUCTION-SWEEPER.

1,192,949.

Specification of Letters Patent.

Patented Aug. 1, 1916.

Application filed September 3, 1914. Serial No. 859,949.

To all whom it may concern:

Be it known that I, JAMES M. SPANGLER, a citizen of the United States, residing at Canton, in the county of Stark and State 5 of Ohio, have invented a new and useful Suction-Sweeper, of which the following is a specification.

My invention relates to suction sweepers and more particularly to means for controlling the motor which operates the fan in 10 the sweeper.

The object of my invention is to provide a suction sweeper in which the fan motor is controlled by the operating handle.

15 A further object is to provide a suction sweeper in which the fan motor is caused to operate when the handle is moved into the operative position and in which the motor is automatically stopped when the handle is 20 raised into the inoperative position.

A still further object is to provide a suction sweeper of the character referred to in which the handle is normally held in the 25 inoperative position.

25 A still further object is to provide means whereby the circuit through the fan motor is completed when the operative handle is moved into the operative position and in which the circuit is broken when the handle 30 is moved out of the operative position.

With these objects in view the invention consists in the novel construction and arrangement of parts, hereinafter described, 35 illustrated in the accompanying drawings, and particularly pointed out in the appended claims, it being understood that various changes in the form, proportions, size and minor details of construction may be made without departing from the spirit or sacrificing any of the advantages of the invention.

40 In the accompanying drawings: Figure 1 is a perspective view showing the operating handle in the inoperative position. Fig. 2 is a similar view showing the operating handle in the operative position. Fig.

45 Fig. 3 is a perspective view of the portion of the switch which is carried upon the casing of the sweeper. Fig. 4 is a perspective view 50 of the portion of the switch which is carried upon the operating handle. Fig. 5 is a transverse vertical section through the portion of the switch shown in Fig. 3. Fig. 6 is a similar section showing the two switch 55 members in engagement. Fig. 7 is an in-

terior face view of one of the insulating blocks carried upon the sweeper casing showing the contact plate carried thereby. Fig. 8 is a similar view of the other insulating block and contact plate. Fig. 9 is a 60 transverse vertical sectional view showing a means for normally holding the operating handle in inoperative position. Fig. 10 is a bottom plan view of the switch blades and insulating block by which they are attached to the handle. 65

Similar numerals of reference indicate corresponding parts throughout the several figures of the drawing.

In the ordinary form of electrically operated suction sweeper it is necessary to provide some form of electrical switch upon the sweeper in order to turn on the current when it is desired to operate the sweeper and also for turning off the current when 70 the sweeper is not in use. In the ordinary form of sweeper, above referred to, the switch must be manually operated to start or stop the motor. It often occurs that through thoughtlessness or carelessness the 75 motor is left running when the sweeper is not in use. To obviate this difficulty I have provided means whereby the motor is started when the handle of the sweeper is lowered into the operative position and stopped when 80 the handle is raised into the inoperative position and means for holding the handle in the inoperative position when the sweeper 85 is not in use.

Referring more specifically to the construction illustrated in the accompanying drawings, the numeral 1, indicates generally the casing of a suction sweeper provided with the fan housing 2, motor 3 and dust receptacle 4 all of which are of the usual 90 construction and need no further description here. The operating handle 5 of the sweeper, is provided with the bifurcated fork 6, the arms 7 of which are pivotally connected at 8 upon either side of the 100 sweeper casing.

Two segments 9 and 10, formed of fiber or other suitable insulating material are spaced apart by means of a block 11 of the same material and are connected together 105 and to a bracket 12, which is carried upon the motor casing 2, by any suitable means as by the screws 13. A pair of segmental, metallic, contact plates 14 and 15 are embedded in the interior faces of the insulated 110

segments 9 and 10 respectively. It should be noticed that the contact plates 14 and 15 are located in an arc, the center of which would be on a line connecting the two pivotal points 8 of the fork 6, the reason for this construction being hereinafter described and pointed out.

A cable 16, connected to any suitable source of electricity contains the wires 17 and 18 which are properly insulated apart. The wire 17 leads to the motor 3 and the wire 18 is connected to the contact plate 15 at 19. A wire 20 leads from the motor and is connected to the contact plate 14 at 21.

The switch blade is formed of a strip of conducting metal bent back upon itself for a portion of its length, said portion 22 being located within a slot in the insulating block 23, said insulating block being formed of fiber or other suitable material. The switch blade is permanently held in position within the fiber block 23 by means of a set screw or the like 24 and the switch block is connected to one of the arms 7 of the fork 6 which carries the operating handle by screws 25 and 26. The screw 26 passes through an enlarged aperture in the portion 22 of the switch blade in order that the screw does not contact with any portion of the switch blade, for the purpose of preventing the arms 7 and other portions of the casing from becoming electrically charged. The ends of the strip which forms the switch blades are separated at the point where they emerge from the insulating block 23 and are slightly inclined toward each other as shown in Fig. 10, thus forming two integral spring blades 27.

A substantially triangular plate 28 is connected at its base to the casing 1 at a point adjacent the pivotal point of one of the arms 7 of the handle, preferably by one of the screws 8 and a screw 29. An aperture 30 is located near the apex of the plate 28 and is adapted to accommodate a screw head 31 or other suitable lug provided upon the arm 7, when the handle 5 is raised into the inoperative position, thus holding the handle in the inoperative position. The upper rear edge 50 of the plate 28 is turned outward at 32 to allow the screw head 31 to pass the plate 28 when the handle is raised in the position shown in Fig. 1, the screw head 31 springing the upper end of the plate 28 outwardly 65 until the aperture 30 in the plate registers with the screw head at which time the plate will spring back causing the screw head to enter the aperture 30 as best shown in Fig. 9 thus holding the handle in the upright position.

It will be seen that one end of the electrical circuit passes through the motor and connects with the contact plate 14 and the other end of the circuit connects with the contact plate 15 thus leaving the circuit

open. When it is desired to operate the sweeper the handle 5 is lowered into the position shown in Fig. 2 of the drawing, the spring switch blade 27 contacting with the contact plates 14 and 15 as best shown in Fig. 6 of the drawing thus completing the electrical circuit and starting the motor. As long as the machine is in operation, that is, as long as the handle 5 is held in operative position as shown in Fig. 2 which is the natural position when operating the sweeper the circuit will remain unbroken and the motor will continue to revolve. When it is desired to discontinue the use of the sweeper it is only necessary to raise the handle 5 into the position shown in Fig. 1, at which time the switch blades 27 will be drawn out of contact with the contact plates 14 and 15 breaking the circuit and stopping the motor, the spring plate 28 holding the handle in this position and preventing the motor from being started until it is again desired to use the sweeper.

Although the drawings and above specification disclose the best mode in which I have contemplated embodying my invention I desire to be not limited to the details of such disclosure, for, in the further practical application of my invention, many changes in form and construction may be made, as circumstances require or experience suggests, without departing from the spirit of the invention, within the scope of the appended claims.

I claim:

1. In a suction sweeper, the combination of a motor casing and a fan casing, a motor, a handle pivoted upon said fan casing, contact plates carried upon said motor casing, an electrical circuit, one wire of said circuit passing through said motor and connected to one of said contact plates, the other wire of said circuit connected to the other of said contact plates and means upon said pivoted handle for completing said circuit, and means for normally holding said pivoted handle in the inoperative position.

2. In a suction sweeper, the combination of a casing, a motor pivoted upon said casing, a bracket carried upon said casing, contact plates carried by said bracket, said contact plates insulated from said bracket and from each other, an electrical circuit, one wire of said circuit passing through said motor and connected to one of said contact plates, the other wire of said circuit connected to the other of said contact plates, an insulated block carried by said handle and a bifurcated switch blade carried by said insulated block and adapted to contact with both of said contact plates when said handle is moved into the operative position.

3. In a suction sweeper, the combination of a motor casing and a fan casing, a handle pivoted to the fan casing, a bracket carried

upon said motor casing, contact plates carried by said bracket, said contact plates insulated from said bracket and from each other, an electrical circuit, one wire of said circuit passing through said motor and connected to one of said contact plates, the other wire of said circuit connected to the other of said contact plates, an insulating block carried by said pivoted handle, a bifurcated switch blade carried by said insulated block and adapted to contact with both of said contact plates when said pivoted handle is moved into the operative position.

4. In a suction sweeper, the combination of a motor casing and a fan casing, a handle pivoted to the fan casing, a bracket carried upon said motor casing, contact plates carried by said bracket, said contact plates insulated from said bracket and from each other, an electrical circuit, one wire of said circuit passing through said motor and connected to one of said contact plates, the other wire of said circuit connected to the other of said contact plates, an insulating block carried by said pivoted handle, a bifurcated switch blade carried by said insulated block and adapted to contact with both of said contact plates when said pivoted handle is moved into the operative position, and means for normally holding said pivoted handle in the inoperative position.

5. In a suction sweeper, the combination of a fan casing and a motor casing, a motor located within said motor casing, a handle pivoted upon said fan casing, a bracket carried by said motor casing, a segmental insulating block provided with a vertical slot, an electrical circuit, one wire of said circuit passing through said motor and connected to one of said contact plates and the other wire of said circuit connected to the

other of said contact plates, a switch blade carried upon said pivoted handle and insulated therefrom and adapted to contact with said contact plates when the pivoted handle is moved into the operative position and means for normally holding said handle in inoperative position.

6. In a suction sweeper, the combination of a motor casing and a fan casing, a motor, a handle pivoted upon said fan casing, contact plates carried upon said motor casing, an electrical circuit, one wire of said circuit passing through said motor and connected to one of said contact plates, the other wire of said circuit connected to the other of said contact plates and a switch blade upon said handle adapted to contact with both of said contact plates when said handle is moved into the operative position.

7. In a suction sweeper, the combination of a motor casing and a fan casing, a motor, a handle pivoted upon said fan casing, contact plates carried upon said motor casing, an electrical circuit, one wire of said circuit passing through said motor and connected to one of said contact plates and the other wire of said circuit connected to the other of said contact plates, a switch plate upon said handle adapted to contact with both of said contact plates when said handle is moved into the operative position and means for normally holding said handle in the inoperative position.

In testimony that I claim the above, I have hereunto subscribed my name in the presence of two witnesses.

JAMES M. SPANGLER.
